UNITED STATES PATENT OFFICE.

CHARLES E. HARTIAN, OF LYNN, MASSACHUSETTS, ASSIGNOR TO THE
GENERAL ELECTRIC COMPANY, OF NEW YORK.

DESIGN FOR A CASING AND SUPPORT FOR ELECTRIC-ARC LAMPS.

SPECIFICATION forming part of Design No. 31,146, dated July 4, 1899.

Application filed June 20, 1898. Serial No. 684,008. Term of patent 14 years.

To all whom it may concern:

Be it known that I, CHARLES E. HARTIAN, a citizen of the United States, residing at Lynn, in the county of Essex, State of Massachusetts, have invented and produced a certain new and useful Design for a Casing and Support for an Electric-Arc Lamp, (Case No. 838,) of which the following is a description.

The leading feature of my design consists in (10) an inclosing casing for an electric-arc lamp, together with its support, substantially as shown, and described hereinafter.

The accompanying drawing shows an embodiment of my invention, in which—

(15) D represents the main body of the casing. Secured to the upper end of the casing is a cornice C and to the lower end a cornice E. These cornices are reversed with respect to each other. Situated above and covering the

end of the cornice C is a canopy J, and situated below the cornice E is an outwardly flaring flange F, which is designed to cover the upper portion of the globe. Extending upwardly from the canopy J is a support B, and mounted on the upper end thereof is a canopy A, which canopy is reversed with respect to C.

I claim—

The design for a casing and support for an electric-arc lamp, substantially as shown and (30) described.

In witness whereof I have hereunto set my hand this 16th day of June, 1898.

CHARLES E. HARTIAN.

Witnesses:

DUGALD MCKILLOP,
JOHN McMANUS.
